FOUNTAIN PEN SUPPORT

Lawrence Griffith, Yonkers, N. Y.

Application November 7, 1932. Serial No. 641,525

12 Claims. (Cl. 120—108)

An important object of the present invention is to provide improved means for supporting the closure cap of a fountain pen in a position to serve as a convenient desk holder for the 5 pen.

Other objects of the invention will appear hereinafter.

In the drawing, Fig. 1 is a side view of one 10 form of the improved pen support, with a supported pen;

Fig. 2 a top plan view of said pen support and pen;

Fig. 3 an end view, partly in section, of the 15 attaching stud on the cap of the fountain pen, together with a rear view of the supporting ear which interlocks with said stud;

Fig. 4 a sectional side view of the fountain 20 pen cap and its attaching stud;

Fig. 5 an end view of a modified form of the 25 attaching stud;

Fig. 6 a longitudinal sectional view of the cap provided with said modified stud;

Fig. 7 a view showing a modified mounting 30 for the supporting ear on the base of the support;

Fig. 8 a sectional side view of another type 35 of pen cap equipped with the attaching stud;

Fig. 9 a side view of the latter cap from a different angle;

Fig. 10 a longitudinal sectional view of a portion 40 of a cap equipped with an attaching stud of further modified form;

Figs. 11 and 12 are an end view and side 45 view respectively of the stud shown in Fig. 10;

Fig. 13 a side view showing said stud mounted 50 in a modified form of supporting member; and

Fig. 14 a plan view of said modified supporting member.

Referring to the form of the invention shown 55 in Figs. 1 to 4 inclusive, the pen support includes a base to rest upon a desk or table. The base comprises a lower or sub-base section 1 and an upper section 2, smaller in plan, secured to the upper surface of the sub-base. Forward of the upper base section 2 the sub-base has a pencil-retaining groove 3. At its upper surface the base section 2 is integrally formed with a flat, rigid ear 4 which projects upward and is inclined rearward. The base section 2 is formed 60 of metal or other suitable material permitting the ear to be integrally formed thereon in a convenient manner. The ear has a straight central slot 5 extending downward from its upper edge.

55 The slotted ear 4 forms a support for the

closure cap 6 of a fountain pen P. In general, said cap is of a standard form. It comprises a tubular barrel or bed closed at one end, as at 7, and having an internal screw thread 8 to secure it to the pen P by engagement with a thread 9 60 on the barrel of the pen. Within the cap there is fitted the usual inner tubular section 10 to enclose the nib of the pen. The cap is provided with the usual spring clip 11 to attach it to a pocket. At its closed end the cap has means to 65 interlock with the slotted supporting ear 4 and support the cap in a position to serve as a convenient holder socket for the pen.

The attaching means for the cap comprises a stud 12 formed with a round, flat abutment 70 portion or base 13, a round button-like head portion 14 having a flat inner face, and a medial neck portion 15 joining said base and head. Said neck portion has a straight elongated cross section preferably extending the full diameter 75 of the head. The base 13 is formed with a threaded shank 16 which is screwed into a threaded socket 17 in the closed end of the cap. Preferably the base and head of the stud are 80 of the same diameter as the barrel of the cap. The neck of the stud is proportioned to fit rather snugly into the slot of the supporting ear, and the base and head of the stud are spaced apart to rather snugly receive the ear therebetween. 85 The stud may be formed of hard rubber or other suitable material customarily employed in fountain pen construction.

The cap may be readily mounted to form a parking socket for the pen by merely inserting 90 the neck of the stud transversely into the slot 5. The elongated form of the neck keys it in 95 the slot and holds the cap against turning so that the pen may be unscrewed by twisting its barrel in the cap. When mounted on the supporting ear the cap is firmly supported in an inclined upwardly opening position for convenient 100 insertion of the nib end of the pen. The interlocking engagement of the cap stud with the supporting ear holds the cap positively against endwise shift, and gravity and the fit of the neck in the slot retains the cap against 105 upward displacement from the supporting ear. When the user of the pen desires to remove the pen from the desk and carry the pen and cap with him, the barrel of the pen is twisted to screw it into the cap and the assembled pen and cap are readily detached from the support by a transverse upward and rearward shift to free the attaching stud from the supporting ear. 110

In Figs. 5 and 6 there is shown a modified

form of the attaching stud. Here the stud comprises a button head 14, a round neck 15^a and a threaded shank 16 formed directly on the neck and screwed into the threaded socket 17 at the 5 closed end of the cap. The neck is of greater diameter than the threaded shank and it forms a shoulder to directly abut the end of the cap. This stud also is attachable to a supporting ear similar to the ear 4. The latter may be formed 10 with a wider slot to accommodate the neck 15^a.

In Fig. 7 there is shown a modified mounting for the supporting ear 4. Here the upper base section 2 is omitted and the ear has a flat integral base flange or foot 18 secured by screws 15 or other means directly to the upper surface of the base 1.

Figs. 8 and 9 show the attaching stud mounted upon another well-known form of fountain pen cap. This cap includes a tubular barrel section 20 19 open at both ends. At the stud end of the cap the barrel has an internal screw thread 20 into which is screwed a threaded tubular plug 21 to enclose the nib of the pen. At its outer end said plug has an attaching plug structure 25 similar to that shown in Figs. 1 to 4 inclusive and including the base flange 13, the button head 14 and the transversely elongated neck 15. The cap has a clip 22 formed with an attaching ring 23. The latter surrounds the tubular plug and is clamped between the base flange 13 of the 30 stud and the adjacent end of the cap.

Figs. 10, 11 and 12 show a further modified form of the attaching stud. This stud includes a base or abutment disk 24 also formed with the shank 16 which is screwed into the cap socket 17. At its outer face the disk 24 is formed with a head 25 of flat, wedge-like form, tapering transversely of the disk and lying entirely within the diameter thereof. The head 40 is of dovetail form in cross-section, its opposite converging sides being under-cut, as at 26.

To accommodate the stud head 25 there is provided a supporting ear 27 of modified form, shown in Figs. 13 and 14. At its forward face 45 the ear is formed with a slot or channel 28 open at its upper end for insertion of the head 25 and tapering downward correspondingly to the taper of said head. The slot is of dovetail form in cross section, its opposite downwardly converging sides being undercut, as at 29, to interfit with the dovetail head and hold the latter in the slot.

While I have shown and described my invention as employed to support the closure cap of a 50 fountain pen it may also be employed advantageously to support a socket for holding a pencil or like article.

What I claim is:

1. A fountain pen support comprising a supporting member having a slot disposed in an inclined position and open at its upper end, a tubular closure cap for the fountain pen, and attaching means carried by the closed end of said cap and comprising a head and a reduced portion or neck between said head and the closed end of the cap and fitable into said slot through the open upper end thereof to lock the cap positively against endwise displacement and support it positively in a fixed inclined position to serve as a socket to receive and support the fountain pen, said neck being of elongated form in cross section to key it positively in the slot and prevent turning of the supported cap.

2. A fountain pen support comprising a supporting member having a slot formed with under-cut sides, a tubular closure cap for the foun-

tain pen, and a stud-like attaching projection carried by said cap at the closed end thereof and having undercut opposite sides extending crosswise of the closed end of the cap and interfitable with said under-cut sides of said slot to detachably support the cap in a position to receive and support the fountain pen.

3. A fountain pen support comprising a supporting member having a slot disposed in an inclined position and having downwardly converging under-cut sides, a tubular closure cap for the fountain pen, and an attaching projection carried by said cap at the closed end thereof and of tapering wedge-like form crosswise of the cap end, the opposite converging sides of said projection being under-cut to interfit in said slot to detachably support the cap in an inclined upwardly opening position for receiving and supporting the fountain pen.

4. A tubular closure cap for a fountain pen having a stud-like projection at its closed end to attach the cap to a support, said projection being of tapering wedge-like form crosswise of the closed end of the cap and having its opposite converging edges under-cut, for the purpose set forth.

5. A tubular closure cap for a fountain pen having a stud-like projection at its closed end to attach the cap to a support, said projection having straight opposite sides extending crosswise of the closed end of the cap and under-cut, for the purpose set forth.

6. A fountain pen support comprising a supporting member, a tubular closure cap for the fountain pen, and a slidably releasable interlocking supporting connection between the closed end of the cap and said supporting member to support the cap in an inclined upwardly opening position, hold it against endwise shift and permit it to be slid transversely free of the supporting member, said interlocking connection being formed to lock the cap against rotation on the supporting member.

7. A fountain pen support comprising a supporting member having a base to rest on a desk, a tubular closure cap for the fountain pen having an internal screw thread to screw on an external thread on the fountain pen, and a slidably releasable interlocking supporting connection between the closed end of the cap and said supporting member to support the cap positively in a fixed inclined upwardly opening position, hold it positively against endwise shift and permit it to be shifted transversely free of the supporting member, said supporting connection being formed to lock the cap positively against rotation on the supporting member for screwing and unscrewing the fountain pen in the supported cap.

8. A fountain pen support comprising a base, an upwardly projecting forked member supported by the base in an inclined plane and defining an inclined slot opening at its upper end; a tubular closure cap for a fountain pen having a rigid stud projecting longitudinally from its closed end and forming a head portion and a neck portion, said neck portion being slidably fitable downward into said slot through the upper end of the latter and the stud having shoulders at opposite ends of said neck portion engageable with the opposite faces of the forked member at opposite sides of the slot to hold the cap in an inclined position and positively lock it against endwise displacement on the forked member, the cap being removable from the

forked member by sliding it transversely upward along the slot.

9. A fountain pen support comprising a base; guide means supported by said base in an inclined plane and opening at one end; a tubular closure cap for a fountain pen; and an attaching stud carried by the closed end of said cap to interfit said guide means and formed to shift along said guide means and to interlock therewith to support the cap in an inclined position substantially at a right angle to the plane of the guide means and lock the cap positively against endwise withdrawal from the guide means, the cap being removable from the guide means by moving it transversely to shift the attaching stud along the guide means and through the open end of the latter.

10. A fountain pen support comprising a base; guide means supported by said base in an inclined position and opening at its upper end; a tubular closure cap for a fountain pen; an attaching stud carried by the closed end of said cap to interfit said guide means and formed to shift therewith and interlock therewith to support the cap in an inclined position substantially at a right angle to the guide means and positively lock it against endwise withdrawal from the guide means, the cap being remov-

able from the guide means by moving it transversely upward to shift said stud upward through the upper end of the guide means.

11. A fountain pen support comprising a supporting member, a tubular closure cap for the pen, and a slidably releasable interlocking supporting connection between the closed end of said cap and said supporting member to support the cap positively at an inclination, lock it positively against endwise shift and permit it to be slid transversely in one direction free of the supporting member.

12. A fountain pen support comprising a base; a tubular closure cap for the pen; and an interlocking supporting connection between said cap and base comprising an attaching stud on the closed end of the cap and forming a head and a transversely reduced neck portion, and a cap-holding device supported by the base and having a keeper recess to receive said stud neck to hold the cap in an inclined position and positively lock it against endwise displacement on the supporting device, said keeper recess opening in one direction transversely of the supported cap to render the latter removable by shifting it transversely on the holding device.
